UNITED STATES PATENT OFFICE

FRED M. YOUNG, OF RACINE, WISCONSIN

RADIATOR

Application filed September 8, 1930. Serial No. 480,388.

This invention relates to certain new and useful improvements in radiators and refers more particularly to screens for protecting the radiator core from damage.

5 An object of this invention resides in the provision of a protecting screen for a radiator core which is of relatively light construction, but at the same time affords maximum rigidity and resistance to objects striking it.

A more specific object of this invention is to provide a protecting screen for a radiator core which is rounded or bulged outwardly at its central portion to increase its rigidity, and 15 has its edge portions flat and in a common plane to facilitate its attachment to the radiator to be protected.

With the above and other objects in view which will appear as the description proceeds, my invention resides in the novel construction, combination and arrangement of parts substantially as hereinafter described and more particularly defined by the appended claims, it being understood that such 25 changes in the precise embodiment of the hereindisclosed invention may be made as come within the scope of the claims.

In the accompanying drawings, I have illustrated two complete examples of the physical embodiment of my invention constructed according to the best modes I have so far devised for the practical application of the principles thereof, and in which:

Figure 1 is a front elevational view of a 35 conventional industrial type radiator having my improved protecting screen attached thereto;

Figure 2 is a side view of the radiator showing the rounded or bulged shape of the 40 protecting screen;

Figure 3 is a detailed perspective view illustrating the manner of attaching the screen to the radiator; and

Figure 4 is a fragmentary front elevational 45 view illustrating a slightly modified form of my invention.

Referring now more particularly to the accompanying drawings in which like numerals designate like parts throughout the several 50 views, the numeral 1 represents a radiator of

the conventional commercial or industrial type having a core 2. As is well known, the core of a radiator is of delicate construction and is very easily damaged by objects striking it, and to protect the core a screen 3 is provided. The screen has its central portion rounded or bulged outwardly to produce a convex surface, as best illustrated in Figure 2, thereby greatly increasing the rigidity of the screen and providing maximum resistance to objects striking the same. The bulged formation of the screen also provides a considerable space between the screen and the radiator core which further increases the protection afforded the core, and enables the screen to be made of a relatively light material.

In Figures 1, 2 and 3, the screen is illustrated as being formed of conventional expanded metal lath with either square or diamond shaped openings and in the structure shown in Figure 4, the screen is formed of woven wire netting. In both constructions the edges of the screen are flat and disposed in a common plane and the top and bottom edges are fitted with stiffening bars 4 preferably U-shaped in cross section.

The screen is attached to the radiator by screws or similar attaching means 5 passed through the channel stiffening bars 4 and threaded in the adjacent portions of the radiator, and by having its side marginal edge portions tucked under or engaged beneath flanges 6 forming part of the usual radiator construction. The channel stiffening bars may also be attached to the adjacent radiator portions by tack soldering, welding, or any other suitable means, and while the side vertical edge portions of the screen are preferably engaged beneath the radiator carried flanges 6 for the sake of appearance, this is not necessary.

From the foregoing description taken in connection with the accompanying drawings, it will be readily apparent to those skilled in the art to which an invention of the character described appertains, that I provide a novel inexpensive protecting screen for radiators which forms substantially an integral unit thereof, is exceptionally rigid, and

affords maximum protection for the radiator core.

What I claim as my invention is:

1. In combination with a radiator having a core, a protecting screen for the core having its medial portion bulged and four of its edge portions flat and in a common plane, and means for attaching the screen to the radiator.
- 10 2. In combination with a radiator having a core, a protecting screen for the core having its medial portion bulged and all of its edge portions flat and in a common plane, stiffening bars fitted to the top and bottom edges of the screen, and means for attaching the stiffening bars to the radiator.
- 15 3. In combination with a radiator having a core, a protecting screen for the core having its medial portion bulged and all of its edge portions flat and in a common plane, U-shaped channel bars engaged over the top and bottom edges of the screen, and means for attaching the screen to the radiator including radiator carried parts beneath which the sides of the screen are tucked.

25 In testimony whereof I have hereunto affixed my signature.

FRED M. YOUNG.
